(57) **CLAIM**

The ornamental design for a busbar chopper module, as shown and described.

DESCRIPTION

FIG. 1 is a top and rear perspective view of a busbar chopper module showing our new design;

FIG. 2 is a side elevation view thereof;

FIG. 3 is an opposite side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken line portion of the figure drawings is included to show unclaimed subject matter only and forms no part of the claimed designs.
